INVENTOR:

Charles W. Beehler
Robert Burns
Attorney.

UNITED STATES PATENT OFFICE.

CHARLES W. BEEHLER, OF ST. LOUIS, MISSOURI, ASSIGNOR OF ONE-HALF
TO WILLIAM H. LONERGAN, OF SAME PLACE.

BOX-FASTENER.

SPECIFICATION forming part of Letters Patent No. 349,077, dated September 14, 1886.

Application filed July 26, 1886. Serial No. 209,163. (No model.)

To all whom it may concern:

Be it known that I, CHARLES W. BEEHLER, a citizen of the United States, and a resident of St. Louis, in the State of Missouri, have 5 invented certain new and useful Improvements in Box-Fasteners; and I do hereby declare the following to be a full, clear, and exact description of the same, reference being had to the accompanying drawings, forming a part of this 10 specification, in which—

Figure 1 is a perspective view of the fastener proper detached; Fig. 2, a perspective view of one end of an egg-box, showing the end cleats slotted to receive the fastener, with 15 the fastener in its unengaged position; Fig. 3, a detail perspective view of the cover-cleat detached; Fig. 4, a similar view of the box-cleat; Fig. 5, a detail end view of the egg-box, with the fastener in place and in a "locked" 20 position; Fig. 6, a longitudinal section of the same at line 6 6, Fig. 5; and Fig. 7, a horizontal section of the same at line 7 7, Fig. 5.

Similar letters of reference indicate like 25 parts in the several views.

This invention relates to that class of fasteners employed at the ends of egg and other cases to secure the cover in place without other means of fastening; and the present improvement has for its object to supply a fastening 30 device cheap and effective in construction, easy of application, and capable of quick and easy manipulation to release or secure the cover.

To enable others skilled in the art to which my invention appertains to make and use the 35 same, I will now proceed to more fully describe its construction and mode of operation.

Referring to the drawings, A represents the box end, B the cover, C the cover-cleat, and D the box-cleat.

The fastener proper consists of a rectangular staple, E, which is driven into the cover-cleat C, its straight lower bar, e, being clasped by the pivot-eyes f of the inverted-T or anchor shaped fastener-piece F, to form a pivot-joint 45 for the same.

The fastener-piece or anchor F is made of wire bent to the shape shown, with its vertical members f' set so as to spring away from

each other, as indicated in Fig. 1, the purpose being to cause the same to bind in the 50 slots formed for its reception in the cleats C and D, and hold the fastener in any position to which it is set either opened or closed. The upper or cover cleat, C, is cut away at e a sufficient distance to admit of the pivot-eyes f being arranged above the lower edge of said cleat to prevent marring or bending of the fastening by the usual handling of the cover in general use, while the lower or box cleat, D, is provided with a narrow vertical slot, d, to 60 receive the vertical member f' of the fastener F, and form an abutment for the horizontal member f'' of such fastener, as clearly indicated in Fig. 5.

I am aware that prior to my invention box- 65 fasteners have been formed of a spring-loop of wire, and adapted to engage around and under a knob or projection formed by slits or grooves in the box-cleat to form a lock, and also that such form of fastener has been piv- 70 oted in the upper cleat and adapted to engage a similarly-formed projection or knob; but I am not aware of the prior use of an inverted-T or anchor shaped loop of wire pivoted to the upper cleat and adapted to form a lock by 75 engaging in a single vertical slit or groove in the lower box-cleat.

Having thus fully described my invention, what I claim as new, and desire to secure by Letters Patent, is—

1. A box-fastener consisting of a staple, E, secured to the cover-cleat, and an inverted-T or anchor shaped fastener-piece, F, of wire, pivoted thereto, and adapted to engage in a vertical slot in the box-cleat D, and by means 85 of its horizontal member f'' form a lock, essentially as set forth.

2. A box-fastener consisting of a staple, E, secured to the cover-cleat, and an inverted-T or anchor shaped fastener-piece, F, of wire, 90 pivoted at its upper end to the staple E, in combination with the cover and box cleats C D, provided with vertical coincident slots c d, as described, and for the purpose set forth.

3. A box-fastener consisting of a staple, E, 95 of rectangular shape, secured to the cover-

cleat, and an inverted-T or anchor shaped fastener-piece, F, of wire, pivoted thereto, with its vertical members f adapted to spring away from each other, in combination with the box-cleats C and D, provided with narrow slots c and d, the parts being arranged and adapted to operate in the manner and for the purpose set forth.

In testimony whereof witness my hand this 21st day of July, 1886, at Chicago, Illinois.

CHARLES W. BEEHLER.

In presence of—

ROBERT BURNS,

GEO. H. ARTHUR.
